UNITED STATES PATENT OFFICE.

HENRY E. CLINTON, OF AUGUSTA, GEORGIA.

PACKING-CASE.

SPECIFICATION forming part of Letters Patent No. 237,486, dated February 8, 1881.

Application filed December 20, 1880. (Model.)

To all whom it may concern:

Be it known that I, HENRY E. CLINTON, of Augusta, in the county of Richmond and State of Georgia, have invented certain new and 5 useful Improvements in Packing-Cases; and I do hereby declare the following to be a full, clear, and exact description of the invention, such as will enable others skilled in the art to which it pertains to make and use it, reference 10 being had to the accompanying drawings, which form part of this specification.

My invention relates to an improvement in packing-cases for soda-water and beer bottles; and it consists in making the case in two parts, 15 and subdividing each part by a number of cross-divisions into pockets or cells just large enough to receive the bottles, and then separate the bottles from each other when the halves of the case are put together by inserting a sheet of thick paper or pasteboard between them.

It further consists in securing the two parts of the case together by means of hasps and staples, which are applied to opposite ends of 25 the case, and to opposite corners of the ends, as will be more fully described hereinafter.

The object of my invention is to construct a packing-case for the transportation of bottles, and which case is made in two parts, so that 30 the bottles will have their thickest and strongest portions in contact with each other during transportation, and which parts of the case are connected together by means of hasps, which are provided with spring-catches, so as 35 to dispense entirely with locks.

Figure 1 is a perspective of one-half of one of my cases. Fig. 2 is a vertical cross-section taken through the case and showing the position of the bottles. Fig. 3 is an end view of 40 one of the cases.

A represent the two halves of one of my packing-boxes, which are made of a rectangular form, and which are subdivided by a number of cross-partitions into a number of cells 45 or pockets just large enough to receive a lager-beer or soda-water bottle. In filling these halves of the cases with the bottles for transportation, the small ends of the bottles are inserted first, and then the two halves of the 50 case are turned upon their sides, and before

they are brought together a sheet of thick paper, pasteboard, or any thin material is placed between the two. The two halves of the case are then brought in contact with each other and secured together by means of the hasp 55 and staple B, which is applied to each end. By this method of packing the bottles only their thick and strongest ends are brought together, and as the paper or pasteboard placed between them serves to deaden the contact between the bottles, there is not the slightest chance of any of the bottles being broken unless the case is thrown down with considerable force.

Through the end of each one of the halves 65 of the case is cut a hand-hole, C, and in order that the partition inside of the box may not interfere with the hand in moving the case about, the upper portion of the partition is cut away, as shown.

The two halves of the case are secured together by a common hasp and staple, B, and in order to dispense with the use of a lock or other device for fastening the hasp over the staple, the hasp is here provided with two spring-jaws, I, which are placed upon the pivot G. Also, secured upon this pivot is a wire spring, O, the ends of which project out and pass through the corners of the jaws I, and thus force the jaws always together. Before the 80 hasp can be passed down over the staple it is necessary that the inner ends of the jaws, through which the springs pass, should be forced inward toward each other, so as to separate their outer ends, and thus leave the opening 85 through the hasp free for the staple to pass through. As soon as the staple is passed through the opening in the hasp it is only necessary to release the inner ends of the spring-jaws, when the spring will force their 90 outer ends together, and thus lock the hasp upon the staple. In order to prevent these spring-jaws from being opened after the case has been closed, a screw or pin may be passed through the opening P which is made in the 95 hasp, and which screw or other device will prevent the inner ends of the jaws from being forced together. These fastening devices, above described, are placed at diagonally- 100 opposite corners of the case for the purpose of

preventing the hand holes or openings made through the ends of the cases from being interfered with.

Having thus described my invention, I claim—

- 5 1. The combination of a packing-case made of two parts, each part being provided with a series of cells or pockets, with a suitable dividing-partition placed between the cells of the respective parts, and a hasp and staple placed at each end of the case, as and for the purpose described.
- 10 2. A packing-case for the transportation of bottles made in two separate parts, each part

being provided with a series of cells or pockets, in combination with a dividing-sheet, of pasteboard or paper, placed between the cells of the respective parts, and suitable devices for fastening the two parts of the case together, substantially as shown.

In testimony that I claim the foregoing I have hereunto set my hand this 10th day of December, 1880.

HENRY E. CLINTON.
